UNITED STATES PATENT OFFICE.

DAVID McILWRATH, OF NEWCASTLE, INDIANA.

DAMPER ATTACHMENT FOR PIANOS.

Application filed April 21, 1922. Serial No. 555,901.

To all whom it may concern:

Be it known that I, DAVID McILWRATH, a citizen of the United States, residing at Newcastle, in the county of Henry and State of Indiana, have invented new and useful Improvements in Damper Attachments for Pianos, of which the following is a specification.

The object of this invention is to provide means in the actions of grand, upright, and player-pianos, whether hand, foot, or electrically operated, whereby the tone-volume can be reduced from three to either one, or two strings per unison, and to produce an attachment to the piano action of specially arranged group mutes or dampers which are operated by the regular foot-pedals in hand-playing pianos or by lever or automatic equipment in player-pianos, whether foot or electrically operated. This appliance reduces or subsides the volume of tone in desired sections of the piano, as above described.

A further object of this invention is to provide a device for the above purpose which can be applied to either grand or upright actions as now used, and, by making the actions stationary will give the same or more pleasing effects and will eliminate the sliding or shifting action in grand pianos when soft or reduced volume is desired.

The object also is to prevent lost motion in upright and player actions caused by the use of the soft pedal as at present equipped and a further object is to prevent much of the wear and frequent action-adjustment now necessary in upright and grand pianos under present methods of construction, and one of my important objects is to produce the sweet dulcimer effects so much desired in the rendition of certain musical compositions.

I accomplish the above, and other objects which will hereinafter appear, by the mechanism illustrated in the accompanying drawings, in which—

Figure 1, is a view in vertical section of the string and hammer mechanism of a standard piano shown in part and with my invention applied thereto and operated by a foot pedal mechanism, as illustrated in full lines and also showing the hand-lever operating mechanism in dotted lines the view being substantially on the line 1—1 of Fig. 2. Fig. 2, is a view in rear elevation of the middle portions of the strings of the pia-

no showing the application of the mutes or dampers and their supporting and operating mechanism comprising the essential features of my invention. Fig. 3, is a section on the line 3—3 of Fig. 2 and Fig. 4 is a like section on the line 4—4 of Fig. 2.

Like characters of reference indicate like parts throughout the several views of the drawings.

The treble strings 5 and base strings 6 are of usual construction for pianos and are vibrated by being struck by a hammer 7, operated by key levers and the usual and suitable mechanism (not shown).

Supported upon and by a board 8 are standards 9 which support brackets 10 and 11 to which bracket supports 3 are fastened and in the ends of these supports a rock-bar 12 is journaled. The dampers 13 are of usual construction. Mounted on the rock-bar 12 is a mute-bar 14 which swings in unison with the rocking movement of the bar 12. Mounted on the mute-bar 14 is a series of felt pads 15 which have tapering sides and are so proportioned and placed as to contact one or two strings, according to the desire of the builder, when the bar 12 is suitably rocked, and by such contact mute the strings contacted.

Generally two strings are rendered mute by the contact of the pads 15 with said strings, and a third one or a pair of strings not contacted and allowed to function, produce the dulcimer effect required for the intended rendition of certain musical classics written before the development of the modern piano and not possible of rendition on the latter as now constructed, without my attachment. It is entirely optional as to whether two strings are damped or only one is damped by each pad 15.

A rod 16 is attached to an arm 17 extending from the rock-bar 12, and by a longitudinal movement imparted to the rod 16 the bar 12 is rocked. This movement of rod 16 may be by lever 18 fulcrumed at 19, upon the rear end of which lever the rod 16 is attached and with the front end of which lever a foot-operated pedal 20 is connected. Movement of rod 16 may be imparted through a hand-lever 21 shown in dotted lines in Fig. 1.

The operation of my invention is obvious from the above description, taken with the illustration of the drawing, and while I have here shown the preferred form of my inven-

tion, it is capable of variations, some of which have been specifically mentioned, and I therefore do not desire to be limited to the precise form shown, or any more than 5 is required by the appended claims; and having thus fully described my invention what I claim as new and wish to secure by Letters Patent, is—

1. The combination with a group of treble 10 strings of a piano and a group of bass strings, all substantially in a common plane, of a rock-bar crossing both string groups, means for rocking the bar, a mute-bar fixed to move with the rock-bar and also crossing 15 both string groups, and pads fixed to the mute-bar, each of said pads being adapted to contact one or more of said strings when the rock-bar is rocked in one direction and to be disengaged therefrom when the rock- 20 bar is oppositely rocked.

2. The combination, with the strings of a piano, of a rock-bar, a mute-bar swinging in unison with the rock-bar, tapering pads on the mute bar placed to enter between the strings by the rocking of the rock-bar and 25 manually operated means for rocking the rock-bar.

3. The combination, with the strings of a piano, of a rock-bar crossing all of said strings, a mute-bar fixed to the rock-bar and 30 moving with it, tapering pads fixed on the mute-bar and adapted by the taper to enter freely between a pair of strings, each pad being placed to contact one or more strings in its entered position and manually oper- 35 ated means for moving the pad.

Signed at Newcastle, Indiana, this the 18th day of April, 1922.

DAVID McILWRATH.
